UNITED STATES PATENT OFFICE.

JOSEPH DICK, OF CANTON, OHIO, ASSIGNOR TO THE JOSEPH DICK MANUFACTURING COMPANY, OF CANTON, OHIO, A CORPORATION OF OHIO.

KNIFE-GRINDING MACHINE.

1,199,672.

Specification of Letters Patent. Patented Sept. 26, 1916.

Application filed July 2, 1914. Serial No. 848,574.

To all whom it may concern:

Be it known that I, JOSEPH DICK, a citizen of the United States, residing at Canton, in the county of Stark and State of Ohio, have invented certain new and useful Improvements in Knife-Grinding Machines, of which the following is a specification.

The invention relates to a machine for grinding the beveled edge of straight knife blades used in fodder cutters, planing machines, and the like, wherein a straight edge and a true bevel are necessary or desirable. When such a knife is ground by applying it manually to the face of a grinding element, it is difficult, if not impossible, to grind a straight edge and a uniform bevel, and when a supporting frame for the knife is required to move endwise with respect to a relatively stationary grinding element, the machine requires so much space as to render it impractical or inconvenient for many kinds of use.

The object of the present invention is to provide a grinding machine having a stationary carrying support for the knife and a grinding wheel moving longitudinally thereof, with means for adjusting the knife support, means for automatically moving the grinding wheel to and fro endwise of the knife during the operation of the machine, and means for permitting the grinding element to operate in a stationary position for use in ordinary work.

Ancillary features of the improvement relate to improved means for transmitting power from a relatively stationary main shaft to the oscillating shaft of the grinding element; to improved means for reversing the movement of the grinding element at the ends of its oscillation, and for holding the reversing means against accidental operation; and to means actuated by the rotation of the grinding means for cooling the grinding wheel and the knife blade during the grinding operation.

A preferred embodiment of the invention is illustrated in the accompanying drawings forming part hereof, in which—

Figure 1 is a perspective view of the knife grinding machine; Fig. 2, an end view of the same; Fig. 3, a front elevation of the same; Fig. 4, a section of the grinding head and carrier; Fig. 5, a plan view of the knife grinding machine; Fig. 6, a detached plan view of the reversing bar; Fig. 7, a similar

view illustrating the operation of the reversing bar; Fig. 8, a detached elevation of the belt transmission gearing illustrating the movements thereof; Fig. 9, a fragmentary elevation, partly in section, of the clutch pulley; Fig. 10, a detached perspective view of the clutch lever; Fig. 11, a fragmentary rear view showing the clutch, its lever and its bearing; and Fig. 12, a rear perspective view of the blast nozzle.

Similar numerals refer to similar parts throughout the drawings.

The grinding machine includes the frame 1, the cross heads 2 and 2^a secured on the ends of the frame, the knife holder 3 secured by the adjusting arms 4 to the cross heads, slide bars 5 and 5^a extending between and having their ends secured to the cross heads, the grinding head 6 mounted on the slide bars, the grinding wheel 7 having its spindle 8 journaled in the grinding head, the main pulley 9 on the main shaft 10, the belt gear 11 for the grinding spindle, the bevel gear 12 for the clutch shaft 13, the clutch pulley 14, the reversing belts 15 and 15^a, the reversing pulley 16 and the idle pulleys 17 and 17^a on the worm gear 18 which is journaled in the cross heads, and the reversing rod 19 which is mounted longitudinally on the frame.

The arms 4 for the knife support 3 are adjusted forward and rearward by means of the screw heads 20 and the compression springs 21 located on these arms between the pendent bearings 22 and 22^a on the cross heads, in which the arms are mounted; so that the knife holder 3 may be adjusted to and from the grinding edge 23, of the face of the grinding wheel 7, and the springs will cushion the movement of the supporting arms in one direction. It will be understood that the work of grinding is performed by one peripheral edge only of the grinding wheel, in the manner well known in the art; the knife 24 being secured to the supports 3 by the clamps 25.

The main shaft 10 is journaled in the bearing 26 secured in fixed relation to the frame substantially midway between the ends thereof; and power received by this shaft from the main pulley 9, is transmitted to the grinding spindle 8 by means of the belt gear 11 which passes around the pulleys 27 on the main shaft, the pulley 28 on the grinding spindle, and the idle pulleys 29 110

and 30 journaled on the oscillating arm 31 which rises from a pivotal connection with the main shaft 10.

The upper end of the oscillating arm 31 is bent L shaped to the side opposite the grinding spindle 8, with which spindle it is connected by the link 32 pivoted at one end to the grinding spindle and at the other end to the angle of the L shaped arm 31 between the pivots of the idle pulleys thereon. The construction and arrangement of these parts serves to carry the idle pulleys 29 and 30 in proper relative position to hold the belt gear 11 taut in all the varying positions of the grinding spindle, as it moves to and fro with the grinding head upon the slide bars; which varying positions of the pulleys is shown by broken lines in Fig. 8.

Power is transmitted from the main shaft 10 by the bevel gearing 12 and the clutch shaft 13 to the clutch pulley 14, rotatably mounted on the clutch shaft 13, which in turn is journaled in the sleeve 33, on the clutch arm 34, which sleeve has endwise movement in the pendent bearing 35, depending from the frame. One end of the clutch pulley 12 is provided with the ratchet stops 36 adapted to engage the cross pin 37 on the clutch shaft 13, and the transverse wall 38 in the clutch pulley is abutted by the compression spring 39 which in turn abuts the collar 40, secured on the clutch shaft; whereby the pulley is normally held with its ratchet stops 36 in engagement with the pin 37 on the ratchet shaft, and will be rotated by the shaft, when turning in one direction, but will ride freely thereon when turning in the other direction by the action of the cam faces 41 on the stops 36, which move the pulley endwise against the action of the spring 39 to disengage the stops 36 from the pins 37 on the clutch shaft.

For continuously disengaging the clutch pulley from the clutch shaft, the cam head 42 is formed on the clutch arm 34 and is interposed between the pendent bearing 35 and the adjacent end of the clutch pulley. This head is provided with the socket 43 normally receiving the stops 36 on the end of the pulley, and is also provided with the cam faces 44, coöperating with the lugs 45 on the side of the bearing, so that a rotation of the clutch arm 34 will move the cam head and the clutch pulley endwise upon the clutch shaft and carry the stops 36 on the pulley out of the path of the pins 37 on the clutch shaft, so that a rotation of the same will not turn the pulley. The cam head will remain in this position by the entrance of the lugs 45 into the depression 46 at the ends of the cam faces 44, until the head is again rotated by the arm 34 to permit a return of the pulley stops into engagement with the shaft pins by action of the spring 39.

The grinding head 6 is mounted on the slide rods 5 and 5^a by means of the slide bearings 47 and 48, and is moved to and fro lengthwise on the slide bars by means of the screw shaft 18, operating in the screw bearing 49 formed in the grinding head. Power is communicated to the screw shaft 18 by means of the pulley 16 secured thereto, and either one of the reversing belts 15 or 15^a; while the other belt travels on one of the idle wheels 17 or 17^a located one on each side of the pulley 16. The reversing belts are shifted from one pulley to another, by the reversing rod 19, which has endwise movements in bearings 49 in the cross heads.

Reversing stops 50 and 50^a are adjustably secured on the end portions of the reversing bar, which stops have yoked fingers 51 and 51^a, extending upward around the screw shaft 18 in the path of the screw bearing 49; and the parts are so arranged that when the grinding head is carried in one direction, the screw bearing thereon impinges the stop fingers of the corresponding reversing stop, and moves the reversing rod 19 endwise, which movement shifts one reversing belt from and the other reversing belt upon the reversing pulley 16, by means of the looped arms 52 and 52^a which engage the respective belts.

The action of the reversing rod is rendered positive and certain, and the proper belt is maintained upon the reversing pulley 16, by means of the spring 53 having one end secured to the frame by the bracket 54, and the other end connected to the reversing rod 19 by the link 55, the resilience of the spring normally pressing the pivoted end of the link inward toward and in contact with the reversing rod, as shown in Fig. 6.

When the grinding head is carried by the worm gear toward one end of the frame the stop fingers on the reversing rod are impinged by the screw bearing, and the reversing rod is carried endwise with the grinding head until the end of the spring 53 is forced outward by the pivoted link 55 and this link assumes a position perpendicular to the reversing rod; after which a further endwise movement of the reversing rod carries the link beyond the perpendicular position, whereupon the energy of the spring, acting through the link, thrusts the reversing rod endwise to bring the proper belt fully upon the reversing pulley to reverse the rotation of the same; after which the spring 53, acting through the link 57, holds the reversing rod and the corresponding belt in this position until the grinding head approaches the other end of the machine, whereupon a similar reversing operation is repeated.

The fan case 58 is formed or secured on the grinding head 6, preferably adjacent to the inner side of the grinding wheel, and

the centrifugal fan 59, is secured to the grinding spindle 8 within the fan case. The flexible tube 60 is connected at one end to the outlet 61 of the fan case, and at the other end to the blast nozzle 62, which in turn is supported by the rod 63 having endwise adjustment in the bearing 64 formed or secured on the grinding head. The blast nozzle 62 is bent to bring its free end adjacent to and parallel with the grinding edge 23 of the rim of the grinding wheel 7; and this end is preferably provided with the longitudinal slot 65, so positioned as to discharge a blast of air against the grinding edge of the wheel and the edge of the knife where the same is being ground, for cooling the same; it being understood that the same rotation of the grinding spindle which turns the grinding wheel, also rotates the centrifugal fan for creating the cooling blast of air.

I claim:

1. A grinding machine including a frame, transverse bearings in the frame, a grinding wheel having a transverse spindle operatively mounted on the frame, a knife support at one side of the grinding wheel having arms mounted in the transverse bearings, and spring controlled means for adjusting the arms endwise in the bearings for moving the support directly to and from the side of the grinding wheels.

2. A grinding machine including a knife support, a grinding wheel, means for operating the grinding wheel, coöperating means connected with the operating means for moving the grinding wheel endwise of the knife support, and means for disconnecting the coöperating means.

3. A grinding machine including a knife support, a grinding wheel, means for operating the grinding wheel, coöperating means connected with the operating means for moving the grinding wheel endwise of the

knife support, and means for releasing the coöperating means when the operating means turn in one direction only.

4. A grinding machine including an oscillating grinding spindle, a relatively stationary main shaft, and a gearing including pulleys secured on the shaft and on the spindle, an oscillating arm pivoted on the shaft having an angle on its oscillating end, idle pulleys pivoted on the arm on opposite sides of the angle, a link pivoted to the axis of the grinding means and to the angle of the oscillating arm, and a belt on the pulleys.

5. A grinding machine including oscillating grinding means having a screw bearing therein, a screw shaft operating in the screw bearing to oscillate the grinding means, reversing transmission gearing for the screw shaft, an endwise movable reversing rod having stops thereon in the path of the grinding means and having controlling engagement with the reversing gearing, a spring, and a link connecting the spring with the reversing rod for thrusting and holding the rod in one direction when the rod has been moved from the opposite direction to carry the link beyond a perpendicular position.

6. A grinding machine including an oscillating grinding spindle, a relatively stationary main shaft, and a gearing including pulleys secured on the shaft and on the spindle, an oscillating arm pivoted on the shaft, an idle pulley pivoted to the free end of the arm, another idle pulley pivoted on the arm intermediate its ends, a link pivoted to the axis of the grinding means and to the oscillating arm at one side of the plane passing through the pivots of the idle pulleys, and a belt on the pulleys.
